UNITED STATES PATENT OFFICE.

CHARLES S. HOPPER, OF PHILADELPHIA, PENNSYLVANIA.

CAN-OPENER.

SPECIFICATION forming part of Letters Patent No. 634,111, dated October 3, 1899.

Application filed July 27, 1899. Serial No. 725,224. (No model.)

To all whom it may concern:

Be it known that I, CHARLES S. HOPPER, a citizen of the United States, residing at Philadelphia, (Germantown,) in the county of Philadelphia and State of Pennsylvania, have invented certain new and useful Improvements in Can-Openers, of which the following is a specification.

My invention has relation to a can-opener of the type or class wherein a ring is provided with a central pin or spur and with a cutting-blade arranged radially with respect to the pin or spur; and in such connection it relates to the particular construction and arrangement of the device for said purpose.

The principal objects of my invention are, first, to provide a simple, durable, and effective can-opener comprising in its construction a ring or disk adapted to be grasped and turned by the hand of the operator, said ring or disk having a centrally-arranged spur or pin adapted to enter the head of the can and having also a radial slot in which a knife or cutting implement is adapted to slide toward or away from the spur or pin, and, second, to provide a can-opener comprising in its construction a ring or disk, a pin or spur arranged centrally with respect to said disk, and a knife or cutting implement comprising a cutting edge depending vertically through a radial slot of said ring or disk and having an offset or shoulder bearing against the under face of the ring or disk, said cutting edge being carried by a horizontal arm slotted to the stem of the central pin or spur and adapted to be clamped or locked to the ring or disk by a thumb-nut when the nut is advanced upon the stem of the pin or spur.

My invention, stated in general terms, consists of a can-opener when constructed and arranged in substantially the manner hereinafter described and claimed.

The nature and characteristic features of my invention will be more fully understood from the following description, taken in connection with the accompanying drawings, forming part hereof, in which—

Figure 1 is a top or plan view of a can-opener embodying main features of my invention. Fig. 2 is a cross-sectional view on the line xx of Fig. 1. Fig. 3 is a sectional view on the line yy of Fig. 1. Fig. 4 is a

perspective view of the knife or cutting implement, and Fig. 5 is a front view of the cutting edge of said knife.

Referring to the drawings, a represents a disk or ring having its periphery scalloped, as at a' , so that it may be more readily grasped and turned. The ring or disk a is also provided with a lug a^2 , against which the thumb of the operator is pressed in the turning of the said ring or disk a . This disk or ring a is provided with a centrally-arranged spur or pin b , having a pointed end b' , which is adapted to enter the head of a can. The stem b^2 of the pin b extends above the upper face of the ring or disk a and is threaded to receive a nut b^3 for a purpose to be presently explained.

The ring or disk a is preferably provided with four arms, in one of which, a^3 , is arranged a slot a^4 , radial to the central pin or spur b . The knife or cutting implement comprises a cutting edge d , projecting downwardly through the slot a^4 and having an offset or shoulder d' bearing against the under side of the slotted arm a^3 , as illustrated in Fig. 3. The cutting edge is adapted to be slid back and forth in the slot a^4 toward or away from the central pin or spur b , and thus decreases or increases the circular cut to be made in the head of the can. The cutting edge d depends from a horizontal shank d^2 , which is slotted, as at d^3 , to receive the stem b^2 of the central pin or spur b . The shank d^2 may thus be moved back and forth over the arm a^3 within the limits prescribed by the length of its slot d^3 , and when thus moved to required position it is locked against further movement by screwing down the nut b^3 upon the threaded stem b^2 . When so locked, the cutting edge d is held firmly in a vertical position below the slot a^4 by reason of the fact that it is held by its offset or shoulder d' from moving upward and by the taper of its shank d^2 immediately above the cutting-blade proper from moving sidewise or downward.

The cutting edge d , as illustrated in Fig. 5, has its outer face made convex and beveled, as at d^4 , and its inner face made concave, as at d^5 , and for this reason the part to be severed or cut into from the can will be cut out sharply and in a flat condition, while the remaining part of the can-head will be deflected to form a downward flange along the line of severance.

Having thus described the nature and objects of my invention, what I claim as new, and desire to secure by Letters Patent, is—
A can-opener, comprising a ring or disk having a radial slot, a pin or spur depending centrally from the ring or disk and having a threaded stem, a cutting edge adjustable in and depending vertically through the slot of the ring or disk and having an offset or shoulder bearing against the under face of the ring or disk, a horizontal arm or shank carrying said cutting edge and in slotted engagement

with the stem of the spur or pin, and a nut adapted to be screwed down upon said arm or shank to lock the same to said ring or disk, substantially as and for the purposes described.

In testimony whereof I have hereunto set my signature in the presence of two subscribing witnesses.

CHAS. S. HOPPER.
